UNITED STATES PATENT OFFICE.

JOHN Z. COBLENS, OF NEW YORK, N. Y.

DESIGN FOR A FABRIC.

SPECIFICATION forming part of Design No. 17,879, dated November 15, 1887.

Application filed September 9, 1887. Serial No. 249,232. Term of patent 3½ years.

To all whom it may concern:

Be it known that I, JOHN Z. COBLENS, of the city, county, and State of New York, have invented a new and original Design for Fabrics, of which the following is a full, clear, and exact description.

The nature of my design is fully represented in the accompanying drawings, to which reference is made, and in which—

10 Figure 1 is a plan view, and Fig. 2 is a sectional elevation.

The design consists of a central block or square, *a*, surrounded by narrow stripes *b b*, parallel to each other, and the stripes *c c*, also 15 parallel to each other, and which cross the stripes *b b* at right angles. Parallel with the stripes *b b* are the two wider stripes *d d*, and parallel with the stripes *c c* are the parallel wider stripes *e e*, which cross the stripes *d d* at 20 right angles. Outside of the wide stripes *d d* are the narrow parallel stripes *f f*, and outside of

the stripes *e* are the narrow parallel stripes *g*. At the juncture of the stripes *c e g* with the stripes *b d f* are formed the four small spaced squares *h*, which are joined at the adjacent corners by the central small square, *i*. Between the stripes *c e g*, and *c* appear the two parallelograms *j*, and between the stripes *b d f* appear the two parallelograms *k* on each side of the large central square, *a*, and the said square *a*, 25 small squares *i*, and the parallelograms are separated from the stripes by the vertical lines *l*. 30

I claim—

The design for fabric herein shown and described, consisting of the square *a*, squares *h i*, 35 parallelograms *k k j j*, stripes *g e b f*, and wider stripes *d e*, arranged as shown in the accompanying drawings.

JOHN Z. COBLENS.
